[57] CLAIM

The ornamental design for a covered cheese serving tray or the like, substantially as shown.

DESCRIPTION

FIG. 1 is a top perspective view of the covered cheese serving tray or the like showing our new design;
FIG. 2 is a top plan view thereof;
FIG. 3 is a side elevation thereof;
FIG. 4 is a end elevation thereof;
FIG. 5 is a bottom plan view thereof;
FIG. 6 is a cross-sectional view taken along line 6—6 of FIG. 3; and
FIG. 7 is an exploded top perspective view thereof.
